Primary Examiner — Mitchell Siegel

(57) **CLAIM**

The ornamental design for a frontloader, design as shown and described.

DESCRIPTION

FIG. 1 is the perspective view of the frontloader.

FIG. 2 is the left side view of the frontloader.

FIG. 3 is the right side view of the frontloader.

FIG. 4 is the front view of the frontloader.

FIG. 5 is the rear view of the frontloader.

FIG. 6 is the top view of the frontloader; and,

FIG. 7 is the bottom view of the frontloader.
